UNITED STATES PATENT OFFICE.

CHESTER L. HILL, OF LANCASTER, PENNSYLVANIA.

EQUALIZING ROLL-POLISHING DEVICE.

1,059,363.

Specification of Letters Patent. Patented Apr. 22, 1913.

Application filed August 7, 1912. Serial No. 713,884.

To all whom it may concern:

Be it known that I, CHESTER L. HILL, a citizen of the United States, residing at Lancaster, in the county of Lancaster and State of Pennsylvania, have invented certain new and useful Improvements in Equalizing Roll-Polishing Devices, of which the following is a specification, reference being had therein to the accompanying drawing.

This invention relates to an equalizing roll-polishing device for cleaning and polishing the surface of rolls, and is particularly adapted for use in connection with the rolls of a mill for rolling sheet metal, or similar use where a scale is deposited upon the rolls, rendering them uneven and changing their adjustment.

The object of the invention is to provide a device of this class that may be suitably mounted in proper relation to the rolls and in an adjustable manner to have the proper pressure upon the surface of the roll.

Another object of the invention is to provide a device of this kind that shall have an even pressure of its entire surface upon the roll and be self-equalizing.

Still another object being to provide a device simple of construction, containing few parts, and having the wearing parts capable of removal, and the wearing surface so constructed as to be self-cleaning.

With these and other objects in view, my invention consists in certain construction and combination of parts as will hereinafter be fully described and claimed and illustrated in the accompanying drawings which form a part of this application, and in which like figures of reference refer to corresponding parts in all of the views; but it is fully understood that while I have here described my invention as shown, that I do not confine myself to the exact design, as slight changes may be made in the construction and arrangement of the several parts without departing from the spirit of the invention.

In the drawings:—Figure 1, is a top plan view of the device. Fig. 2, is a similar

view, with the polishing surface removed. Fig. 3, is a longitudinal vertical sectional view, taken on the line X—X of Fig. 1. Fig. 4, is a vertical cross sectional view, taken on the line Y—Y of Fig. 1. Fig. 5, is a side elevation of a portion of a rolling machine, showing the device applied thereto.

Referring to the drawings, the device comprises a casing or body member 1, rectangular and box-shaped in form and provided with the sides 2, ends 3, and trunnions or other mounting means 4. Within said casing 1, and to the bottom thereof are secured a series of springs 5, of semi-elliptic or other forms which are arranged in the manner shown, with their ends extending upward. Resting upon the ends of said springs 5, are a series of backing blocks 6, which are connected together by the longitudinal flexible rods 7, extending through the holes 8, in said blocks 6; said blocks 6 being confined by the sides and ends 2, and 3, but having a free vertical movement upon the springs 5. The outer surface of said block 6, is curved transversely of the device to conform to the curve of the roll, and is formed with diagonal ribs 14, spaced apart and forming grooves 9, between their sides. Upon this surface is secured, by the rivets 10, or other suitable means, a polishing material 11, such as asbestos fiber combined with a reinforcing material to provide a fire-proof material covering the ribs 14, and grooves 9.

The device is mounted as shown in Fig. 5, (or in any other suitable manner) in the adjustable bearings 12, with the polishing surface 11, in contact with the surface of the roll 13, and under pressure of the springs 5. As the rolls 13, revolve, the dirt or scale from their surface is scraped off, enters the grooves and drops from the open ends of the same, thus rendering the device self-cleaning.

Having thus described my invention what I claim as new and desire to secure by Letters Patent is:—

A roll cleaning and polishing device comprising a casing member, tension springs

mounted therein, a series of backing-blocks resting on said springs, flexible rods securing said blocks together, ribs formed upon the surface of said blocks, and a polishing material secured upon said ribs and adapted to be held in contact with the surface of the roll by the tension springs.

In testimony whereof I affix my signature in presence of two witnesses.

CHESTER L. HILL.
